FOREIGN PATENT DOCUMENTS

GB 8207770000 * 1/2020

Primary Examiner — Elizabeth A. Albert*(74) Attorney, Agent, or Firm* — Roach Brown McCarthy & Gruber; Kevin D. McCarthy(57) **CLAIM**

The ornamental design for a planter, as shown and described.

DESCRIPTION

FIG. 1 shows a front, top, right-side perspective view of the planter of the applicant's design.

FIG. 2 is a rear, top, left-side perspective view of the planter.

FIG. 3 shows a front view thereof.

FIG. 4 shows a rear view thereof.

FIG. 5 shows a right view thereof.

FIG. 6 shows a left view thereof.

FIG. 7 shows a top view thereof; and,

FIG. 8 shows a bottom view thereof.

The broken lines in FIGS. 1-4 and 7-8 represent portions of the planter for the purpose of illustrating environment and form no part of the claimed design.

1 Claim, 8 Drawing Sheets(56)
